CLOTHES WASHING MACHINE

Homer Bruce Failing, Syracuse, N. Y., assignor of
one-third to Herbert E. Walters and one-third
to Willard E. Jaquith, both of Syracuse, N. Y.

Application June 14, 1933, Serial No. 675,723

6 Claims. (Cl. 68—37)

This invention relates to a clothes washing machine adapted to be used more particularly in public laundries and analogous places where the articles for different owners or different kinds of fabric are placed in separate foraminous or network bags or similar flexible containers which, together with a suitable washing fluid, are introduced into the machine and agitated therein until thoroughly cleansed.

10 The main object of the present invention is to provide simple and efficient means for effecting an intermittent but progressive angular and axial movement of the articles through a series of successive containers for the washing and/or rinsing fluid or fluids from the inlet of the first to the outlet of the last container of the series and in such manner as to effect a thorough washing, rinsing and cleansing of the articles in transit through the series and thus permit a substantially continuous infeed of the soiled articles and outfeed of the cleansed articles for an indefinite period of time without interrupting the operation of the machine.

One of the specific objects is to produce this combined angular and axial movement of the articles by means of a rotary screw conveyor or successive co-axial conveyors, and means for oscillating the same through different angles or arcs in opposite directions or through equal angles in one direction and lesser angles in the reverse direction whereby successive cycles of oscillation will cause one or more complete revolutions of the conveyor.

Another specific object is to provide means whereby the articles to be washed when fed into the inlet of one container will be automatically fed through the entire series of containers and discharged from the last one of the series in a thoroughly cleansed condition.

40 Other objects and uses relating to specific parts of the machine will be brought out in the following description.

In the drawings:—

45 Figure 1 is a perspective view of a clothes washing machine embodying the various features of my invention and including, in this instance a series of four, containers through which the articles to be washed are adapted to be fed, the guide for the operating rack being shown in section.

50 Figure 2 is an enlarged longitudinal vertical sectional view, partly broken away, taken on line 2—2, Figure 1.

55 Figures 3 and 4 are transverse vertical sec-

tional views taken respectively on lines 3—3 and 4—4, Figure 2.

Figures 5 and 6 are enlarged detail vertical sectional views taken respectively on lines 5—5 and 6—6, Figure 2.

Figure 7 is a detail sectional view taken on line 7—7, Figure 5.

Figure 8 is a diagrammatic view representing the differential arcs of movement of the screw conveyor about its axis in reverse directions.

Figure 9 is a perspective view of a portion of the detached toothed rack for rotating the conveyor screw shaft.

Figure 10 is a vertical sectional view similar to Figure 2 showing a modified construction of screw conveyor.

Figure 11 is a vertical sectional view similar to Figure 10 showing a further modified construction of screw conveyor and one of the containers secured thereto.

The construction shown in Figures 1 to 9 inclusive comprises a plurality of, in this instance four, cylindrical containers 1 mounted end to end in co-axial relation upon opposite ends and intermediate standards 2, 2', and 3 for receiving a corresponding number of screw conveyors 4 which are all mounted upon a rotary shaft 5 for simultaneous rotation therewith.

The opposite ends of each cylinder are supported in semi-circular bearings 6 on the adjacent standards 2, 2', and 3 which are adapted to rest upon the floor on which the washer is installed and are suitably secured to the adjacent ends of the containers to hold the latter in fixed relation thereto.

Each of the cylindrical containers 1 is provided with opposite end walls 7 and 7' extending circumferentially around the shaft 5 for receiving and retaining a sufficient quantity of water or other liquid for washing or rinsing purposes, the outer end wall of the first container of the series and corresponding end walls of the other containers being provided respectively with inlet openings 8 and 8' for receiving the clothes to be washed and rinsed, the inlet opening 8 in the outer end wall of the first container of the series being preferably arranged wholly above the shaft 5 while the inlet openings 8' of the remaining containers preferably extend entirely around the shaft, as shown more clearly in Figure 4.

The opposite end wall of each container 1 is provided with an outlet opening 9 extending entirely around the shaft 5 for permitting the discharge of the laundry articles therethrough in a manner hereinafter described.

In public laundries and analogous places where these machines are adapted to be used, the articles for different owners or different kinds of fabric are usually placed in separate foraminous 5 or network bags or similar flexible holders preparatory to washing the articles therein, but obviously the articles may be promiscuously placed in the inlet end of the washing machine if desired.

10 These bags of articles to be washed may be introduced by hand or otherwise into the inlet opening 8 of the first container 1 of the series,

and in order to facilitate this introduction I have shown by dotted lines in Figure 2 an inclined portion 10 of a suitable chute having its lower end registered with the bottom of the opening 8 with sufficient clearance thereabove to allow free entrance of the clothes into the container under their own weight.

20 If desired, the peripheral wall of each container 1 may be divided lengthwise and horizontally into lower and upper sections 1' and 1'' respectively in which case the lower sections 1' and their respective end walls 7 and 7' will be rigidly held 25 in the corresponding bearings 6 while each upper section 1'' may be hinged along one side at 11 to the corresponding side of the lower section 1' and its opposite side provided with a hand-operated locking device 12 cooperating with a 30 keeper 13 for releasably holding the upper section 1'' in its closed position and permitting it to be opened when necessary for inspection or repairs of the interior parts of the machine.

35 The lid sections 1'' may also be provided with relatively small openings 14 normally closed by lids 14' which, when opened permits inspection of the work during the washing process and also permits the introduction of soap powder or other material which may be necessary to expedite the 40 washing of the articles.

45 Each screw conveyor 4 comprises a central tubular hub 15 keyed or otherwise secured to the shaft 5 and provided with a helical blade 16 having its helixes arranged in uniform axially spaced relation and connected by lengthwise bars 17 which are arranged in uniformly spaced relation circumferentially around and in spaced relation to the hub 15 as shown more clearly in Figure 2.

50 The diameters of the screw blades 16 are substantially uniform from end to end and somewhat less than that of the interior of their respective containers 1, all of said conveyors being mounted co-axially upon one and the same shaft 5 for simultaneous rotation about an axis parallel with but in a plane below the axis of the several containers so as to bring the lower edges of the blade 16 into relatively close proximity to the bottom walls of the containers as shown 55 more clearly in Figures 2 and 3.

60 That is, the screw conveyors are arranged to rotate about an axis eccentric to the axis of their respective containers without frictional engagement with the bottoms thereof and for this purpose the radii of the several blades 16 is slightly less than that of the interior of their corresponding containers to cause the lower edges of the blades 16 to travel in close proximity to the bottom walls of their containers while the distance 65 between the remaining portions of the edges of the blades and peripheral walls of the containers will gradually increase from bottom to top to afford ample clearance for the laundry articles 70 as they are moved angularly and axially rela-

tively to the axis of the shaft within their respective containers.

The inlet ends of the several screw conveyors are provided with pockets 18 extending around the adjacent portions of the hub 15 and having 5 their outer ends adjacent the corresponding inlet openings 8 and 8' open and registering therewith for receiving the laundry articles which may be fed through said openings 8 and 8'.

The pockets 18 are provided with closed inner 10 end walls 19 forming continuations of the adjacent portions of the inlet end of the spiral blade 16 but these pockets are preferably provided with radial openings 18' in one side to permit the laundry articles to pass therethrough between 15 the adjacent helixes of the spiral blade 16.

These pockets 18 rotate with their respective screw conveyors 4 and are arranged to form a part of the first two helixes of the blade 16 so that when the laundry articles are introduced 20 through the openings 8 or 8' they will drop into the adjacent pockets 18 and discharge through the radial openings 18' between the adjacent helixes of the conveyor blade 16. Then, as the screw conveyor and pockets 18 are rotated, the 25 articles disposed between the first two helixes thereof will be picked up by the adjacent cross bar 17 and carried circumferentially around and above the horizontal plane of the shaft 5 and allowed to drop to the bottom of the container 30 between the next succeeding pair of helixes where the articles are again picked up by the adjacent bars 17 and carried circumferentially around and above the horizontal plane of the 35 shaft 5 until they are again allowed to drop into the bottom of the tank into the next succeeding pair of helixes, this operation being continued until the articles are finally discharged through the outlet 9 of each container.

The outlet end of each container is provided 40 with a relatively fixed pocket 20 rigidly secured thereto and open at the top to permit the discharge of the articles from between the last two helixes of the screw conveyor as they are carried upwardly around and above the horizontal 45 plane of the axis of the shaft 5 by the adjacent cross bars 17.

The inner end wall 20' of the pocket 20 extends across the horizontal plane of the axis of the shaft 5 and is preferably inclined downwardly 50 and axially toward the adjacent inlet 8' so that the articles which are disposed in the pocket 20 will gravitate downwardly and axially through the opening 8' and into the pocket 18 of the next succeeding conveyor.

55 These operations upon the laundry articles are repeated through each succeeding container 1 and corresponding conveyor 4 until the articles are finally discharged in a thoroughly 60 cleansed condition from the outlet pocket 20 of the last conveyor of the series onto a suitable delivery chute 21, as shown by dotted lines in Figure 2 where they may be collected in any suitable receptacle not shown.

65 Suitable means is provided for oscillating the shaft 5 and several conveyors 4 mounted thereon through different angles or rather through arcs of different lengths and in such manner as to effect one or more complete revolutions of the 70 conveyors following a predetermined number of cycles of oscillation and for this purpose one end of the shaft 5 is extended through and beyond one of its outer end bearings, preferably that nearest the inlet end of the first container of the series, and is provided with a gear 22 meshing 75

with a driving gear 23 which is keyed or otherwise secured to a stub shaft 24 having one end journaled in the adjacent standard 2 and its other end journaled in an additional standard 5 25, Figures 1, 2, 5, and 6.

This stub shaft 24 carries a pair of relatively rotatable pinions 26 and 26' meshing respectively with tooth racks 27 and 27' both of which latter are rigidly secured to a rack bar 28 which, 10 in turn, is slidably mounted in a suitable guide groove 29 on the standard 25, as shown more clearly in Figures 1, 2, 5, 6, and 9, said rack being yieldingly held against the undersides of their respective pinions by means of a leaf spring 30.

15 Any suitable means may be provided for reciprocating the rack bar 28 along the guide groove 29 for alternately rotating the gears 26 and 26' in reverse directions and thereby to effect corresponding reverse rotation of the stub shaft 24 and screw conveyor 4 through the medium of the gears 23 and 22, and for this purpose one end of the rack bar 28 is connected by a link 31 to a rotary eccentric or crank disc 32 which is secured to a rotary driving shaft 33, 20 the latter being mounted upon a suitable bracket 34 or other fixed support, Figure 1.

The shaft 33 may be driven by an electric motor or other suitable power means, not shown.

The pinions 26 and 26' are loosely mounted end 30 to end upon the stub shaft 24 for relative rotary movement, each pinion being adapted to be connected to the stub shaft by a one way drive clutch as shown more clearly in Figures 5 and 6.

The portion of the shaft 24 surrounded by the 35 pinion 26 is provided with a plurality of, in this instance four, peripheral cams 35 adapted to be engaged by a corresponding number of rollers 36 when the pinion is rotated in the direction indicated by arrow x, Figure 6, through the forward movement of the rack bar 28 in the direction indicated by arrow y in the same figure. That is, these rollers are interposed between the cam faces 35 and inner periphery of the pinion 26 so that when the pinion is rotated in the opposite direction from that indicated by arrow x through the forward movement of the rack bar 28, the rollers 36 will be moved to the low points of their respective cams, thus releasing the pinion 26 from rocking engagement with the shaft 50 24.

The portion of the shaft 24 surrounded by the pinion 26' is provided with a plurality of, in this instance four, peripheral cams 35' which are inclined in a reverse direction from those shown in 55 Figure 6. A corresponding number of rollers 36' are interposed between the cams 35' and inner periphery of the pinion 26' for locking said pinion to the shaft when the pinion is rotated in the direction indicated by the arrow m, Figure 5, 60 through the rearward movement of the rack bar 28 in the direction indicated by arrow n, it being understood that when the pinion is rotated in the opposite direction through the reverse movement of the rack bar 28, the pinion 26' will be released from locking connection with the shaft 24.

It will be noted upon reference to Figures 1, 5, and 6 that the rack bar 28 is shown in its extreme rearward position and that the rack 27 70 engaging the pinion 26 is somewhat longer than the rack 27' engaging the pinion 26', the object of which is to cause the rotation of the shaft 5 and its screw conveyor through arcs of different lengths as the rack bar 28 is reciprocated end- 75 wise.

The relation of the pinion 26 and its operating rack bar 27 is such that when the rack bar is moved from its normal forward position rearwardly the full length of its stroke, the corresponding pinion will be moved about its axis 5 through approximately one half revolution as indicated by the arc a in Figure 8, thereby effecting a corresponding angular movement of the stub shaft 24, gears 23 and 22 and screw conveyor as 4. 10

It will be observed that both racks 27 and 27' are mounted upon the same rack bar 28 for simultaneous movement in reverse directions under which conditions the forward movement of the rack bar from its normal position to effect 15 the angular movement of the screw conveyor through an arc of approximately 180 deg., would cause the rack bar 27' to rotate its pinion 26' in the same direction and at the same speed as that of the shaft 24 and screw conveyor 4, during which movement the rollers 36' will remain in contact with the low points of their respective cams 35'.

This angular movement of the pinion 26 and screw conveyor 4 will continue until the rack 25 bar 28 reaches the limit of its rearward stroke but at about the time the rack bar 28 has been moved rearwardly approximately half its stroke or substantially half the length of the rack 27, the rack 27' will have been moved rearwardly 30 out of engagement with its pinion 26', it being understood that the length of the rack 27 is approximately one half that of the rack 27' and that the pinions 26 and 26' are of the same pitch diameter. 35

As soon as the shorter rack 27' has been moved rearwardly out of engagement with its pinion 26', the stub shaft 24 and screw conveyor will continue to be rotated through the remaining half of the rearward stroke of the rack bar 27 under 40 which conditions the pinion 26' will be free to rotate with the stub shaft through the frictional engagement of the balls 36' with the inner periphery of the pinion 26' and cams 35'.

Then, as soon as the rack bar 28 reaches the 45 limit of its rearward movement and is returned through the first half of its return stroke, the pinion 26 will be free to rotate about the shaft 24 in the direction opposite to that indicated by the arrow x, Figure 6, thus preventing the reverse 50 angular movement of the screw conveyor and permitting the latter to remain at rest until the rack 27' re-engages its pinion 26' during the last half of the return stroke of the rack bar.

Under these latter conditions, the pinion 26' 55 will be rotated in the direction indicated by arrow m, Figure 5, thereby effecting a corresponding angular movement of the shaft 24 and screw conveyor 4 through an arc of approximately 90 deg., as indicated diagrammatically by the lines 60 b, Figure 8, it being understood that when the pinion 26' is rotated in the direction indicated by arrow m, it will become locked to the shaft 24 through the medium of the rollers 36' and cams 35', thereby rotating the gears 23 and 22 65 and effecting a corresponding angular movement of the screw conveyor 4 in the direction indicated by arrow o, Figure 5.

During this reverse angular movement of the pinion 26' by its rack 27' the pinion 26 will also 70 be rotated in the same direction opposite to that indicated by arrow x, Figure 6, and at the same speed, due to the fact that both pinions 26 and 26' are of the same pitch diameter.

After the rack bar 28 has returned to its nor- 75

mal or starting positions, the operations of the rack bar 28, pinions 26, and 26' and screw conveyor 4 in reverse directions will be repeated during each cycle of movement of the rack bar so that each cycle of movement of the rack bar will cause the screw conveyor to be moved angularly through different arcs *a* and *b* as indicated diagrammatically in Figure 8.

It will be seen from this diagram that the screw conveyor is moved first in one direction through an arc of approximately 180 deg., and then returned through an arc of approximately 90 deg., these operations being repeated as long as may be desired, resulting in a complete revolution of the conveyor after a predetermined number of cycles of oscillation.

It will also be observed that after the rack 27 has completed its forward stroke to effect the angular movement of the conveyor through an arc 180 deg., it may return through a half stroke without effecting the operation of the conveyor which remains at rest until the return of the rack 27' into engagement with its pinion 26' whereupon the conveyor will be rotated in a reverse direction through an arc of approximately 90 deg., until the rack bar returns to its normal starting position.

The construction shown in Figure 10 is quite similar to that shown in Figures 1 to 4 inclusive except that a supplemental cylinder 40 is secured to the periphery of its spiral blade 16 to rotate therewith within the outer cylindrical container 1 and is preferably foraminous in that its peripheral wall is provided with a multiplicity of relatively small perforations to allow the washing or rinsing fluid to pass therethrough.

In the construction shown in Figure 11, the outer stationary cylindrical container 1, shown in Figure 10, is omitted and the supplemental cylinder as 40' is secured to the periphery of the spiral blade 16 in a manner somewhat similar to that shown in Figure 10 to rotate with the shaft 5, but is preferably imperforate for the purpose of retaining a quantity of washing or rinsing fluid therein.

In each of the modifications shown in Figures 1 to 4 inclusive and in Figures 10 and 11, the spiral blade or screw 16 and connecting bars 17 are foraminous in that they are provided with a multiplicity of small openings to allow the circulation of the liquid therethrough to and from the spaces between the helixes.

It is to be understood, however, that the modified containers shown in Figures 10 and 11 will be arranged end to end in sequence in a manner somewhat similar to that shown in Figure 1 and that the screw conveyors in the several containers will be mounted upon a single shaft as 5 to oscillate therewith in the manner previously explained for the construction shown in Figures 1 to 4 inclusive.

Operation

Assuming now that the several containers 1 are arranged end to end coaxially in the manner shown in Figures 1 and 2, and that each container contains a predetermined quantity of washing or rinsing fluid and that the several screw conveyors are being oscillated in the manner previously described;

The bags containing the articles to be washed or the individual articles are then fed by hand or otherwise through the inlet 8 into the first container of the series to be discharged in the corresponding receiving chamber or pocket 18 which articles, together with the washing or rins-

ing fluid, will tend to gravitate toward the bottom of the container and between the adjacent helixes of the corresponding screw so that when the latter is oscillated through an arc of approximately 180 deg., the articles will be carried from the bottom upwardly in the direction of rotation some distance above the horizontal plane of the shaft 5 and at the same time will be fed successively by and between the helixes of the screw conveyor until finally discharged from the first conveyor of the series into the pocket 20 thereof.

As the screws continue to rotate the articles discharged in the pocket 20 of the first container will gravitate through the inlet opening 8' into the pocket 18 in the inlet end of the next container of the series where the operation upon the articles is repeated.

In like manner, the articles are successively fed from one container to the other until finally discharged from the outlet pocket 20 of the last container of the series into a suitable receptacle, not shown.

It will now be evident from the foregoing description of the operation of the rotary screw conveyor that the articles to be washed or rinsed, together with the washing or rinsing fluid, are vigorously agitated in each of the containers by being oscillated back and forth through arcs extending about the axis of the agitator or conveyor and by being reciprocated axially of the container in first one direction and then in the opposite direction by the screw action of the conveyor blades during the oscillatory movement thereof. Furthermore, it will be observed that owing to the degree of oscillation of the conveyor or agitator, the cross members 17 will be rapidly moved thereby, in first one direction and then in the opposite direction and will thus be caused to strike against the clothes from first one side and then from the other side and to carry the clothes, after coming in engagement therewith, upwardly along the corresponding side of the container until they drop by their own weight from these members and tumble inwardly and downwardly to the bottom of the container.

Thus, the clothes are vigorously subjected to the action of the washing or cleansing fluid in each container and at the same time are progressively moved through the containers from the inlet to the outlet ends thereof and from one container to the next owing to the fact that the conveyor in each container is rotated in opposite directions through unequal radial angles whereby the conveyors are caused to make complete successive revolutions.

The number of oscillations of the conveyor or agitator required to complete each revolution thereof is a factor controlled by varying the angle of difference between each successive oscillatory movement of the conveyor. The period of time the clothes remain in each container obviously depends upon this latter degree of movement of the conveyor combined with the speed of operation thereof together with the length of the container so that if the treatment of the clothes in the cleansing fluid in one container requires a more or less period of time than in other containers, this may be readily compensated for so that there will be no loss of time in any of the washing operations by providing containers and conveyors of proper lengths.

It will thus be seen that I have provided a washing apparatus wherein articles to be washed may be continuously fed into the inlet end of the first container and acted upon so that the articles will be thoroughly treated in each in-

dividual washing compartment and automatically moved from one cleansing operation to the next and finally be discharged at the outlet end of the last container in a thoroughly washed and 5 cleansed condition, thus producing an apparatus adapted to perform what may be termed a continuous washing operation.

What I claim is:

1. In a laundry washing machine, a rotary screw conveyor adapted to receive laundry articles at one end and to discharge them at its other end, means for retaining a washing fluid between the helixes of the conveyor blade, and means for rotating the conveyor on its axis alternately in opposite directions through unequal radial angles.
2. In a laundry washing machine, a horizontally disposed cylindrical container for the washing fluid and articles to be washed, said container having an inlet opening and an outlet opening for the reception and exit respectively of said articles, and means including a spiral blade mounted in the container for alternately moving said articles axially of the container in reverse 25 directions and about the axis of the container through arcs of different lengths whereby the articles will be progressively moved through the container and washing fluid from the inlet opening to said outlet opening.
3. In a laundry machine, a horizontally disposed cylindrical container for the washing fluid and articles to be washed, said container having an inlet opening and an outlet opening for the reception and exit respectively of said articles, and means including a spiral blade mounted in the container for alternately moving the articles axially of the container in reverse directions and about the axis of the container through an arc 35 of approximately one hundred and eighty degrees (180°) in one direction and approximately ninety degrees (90°) in the opposite direction whereby the articles will be progressively moved through the container and washing fluid from the inlet opening to said outlet opening.

4. In a laundry washing machine, a horizontally disposed rotary screw conveyor adapted to receive laundry articles at one end and to discharge them at its other end, means for retaining a washing fluid between the helixes of the conveyor blade, longitudinally extending bars connecting the helixes of the conveyor, and means for rotating the conveyor on its axis alternately in opposite directions through unequal radial angles.

5. In a laundry washing machine, a plurality of coaxial washing fluid containers each having an inlet in one end and an outlet in its other end for the reception and exit respectively of the articles to be washed, the inlet end of each succeeding container being closely adjacent the exit end of the preceding container and arranged to receive the articles therefrom, each container having a rotary screw conveyor therein for feeding the articles from its inlet through its outlet and into the inlet of the next succeeding container, and means for alternately rotating the conveyors in reverse directions about a common axis through arcs of different lengths.

6. In a laundry washing machine, a horizontally disposed stationary container for the washing fluid, said container having an inlet in one end and an outlet in its other end for the reception and exit respectively of the articles to be washed, a foraminous supplemental container rotatably mounted in the first mentioned container and having an inlet and an outlet arranged to register with the inlet and outlet respectively of the first mentioned container for receiving the articles therein and for discharging them therefrom through said inlets and outlets, a spiral blade mounted in the supplemental container, and means for rotating the supplemental container and blade in unison on their axes alternately in opposite directions through unequal radial angles.

HOMER BRUCE FAILING.
